CARL E. EKLIND AND WILLIAM W. DARROW, OF CHICAGO, ILLINOIS, ASSIGNOR TO CAMEL COMPANY, OF CHICAGO, ILLINOIS, A CORPORATION OF ILLINOIS

SLIDING-DOOR FITTING

Original application filed July 10, 1925, Serial No. 42,639. Divided and this application filed September 20, 1926. Serial No. 136,698.

The present invention relates to sliding door fittings.

More particularly the present invention relates to fittings for sliding doors of railway freight cars. The present application constitutes a division of application Serial No. 42,639, filed July 10, 1925, by the present applicants.

An object of the present invention is to provide a construction applicable to the sliding doors of railway freight cars, which construction will guide the bottom of the door, which will be sturdy, and which will effectually shed water.

15 A further object is to provide an improved sliding door mounting for cooperation with car frames of usual construction.

A further object is to provide a sliding door mounting of improved simplicity and 20 sturdiness over prior practice.

A further object is to provide a sliding door construction which will withstand the effects of weather in an improved manner over prior practice.

25 Further objects will appear as the description proceeds.

Referring to the drawings—

Figure 1 is a fragmentary view illustrating part of the side of a railway box car 30 showing the upper part of a sliding door applied thereto;

Figure 2 is a sectional view taken along the plane indicated by the arrows 2—2 of Figure 1;

35 Figure 3 represents a detail of construction;

Figure 4 is a view similar to Figure 1 but showing the lower part of the sliding door;

Figure 5 is a sectional view taken along the plane indicated by the arrows 5—5 of Figure 4; and

Figure 6 is a perspective view illustrating a detail of construction.

The numeral 1 indicates the side wall of a 45 railway box car, and the numeral 2 indicates a sliding door. Attached at the top of the sliding door 2 are the brackets 3—3, which provide supporting means for the rollers 4—4. Said rollers bear on the upper surface 50 of the track 5. Said brackets 3—3 also pro-

vide supports for the rollers 6—6 adapted to bear against the under side of the track 5, whereby to limit upward movement of the door 2 and prevent sticking of said door.

The numeral 7 indicates a structural steel 55 member which meets the standards of the American Railway Association for side plates for railway cars. Said structural steel member takes the form of a Z-bar having the vertically arranged forward flange 8. The track member 5 is riveted to said forward flange 8 of the structural steel member 7. Said track member 5, which is shown in perspective in Figure 3, comprises the flanges 9 and 10, which are disposed in substantially right 60 angular relationship relative to one another. The flange 9 is adapted to abut against the outer surface of the flange 8 of the structural steel member 7. The flange 10 occupies a substantially horizontal position. Depending from the under side of the flange 10 intermediate of the width thereof is the 65 flange 11.

Mounted upon the upper edge of the door 2 is the Z-bar 12, having the upwardly extending flange 13 lying back of the flange 11 of the track member 5. The forward flange 14 of the Z-bar 12 lies along the front surface of the door 2 at the upper extremity thereof, and is riveted to the brackets 3—3. 70

Mounted at the bottom of the door 2 is the T-shaped structure 15 having the leg portion 15' underlying the bottom edge of said door and having the upwardly extending flange 16, which may be gained into the rear 85 side of the door 2. The downwardly extending flange 17 of the T-shaped structure 15 lies in rear of the brackets 18, which brackets 18 are secured to the car frame. It will be clear that the upwardly extending flange 13 of the Z-bar 12 and the downwardly extending flange 17 of the T-shaped structure 15 will cooperate with the downwardly extending flange 11 of the track member 5 and with the brackets 18, respectively, to limit 90 outward movement of the door 2.

Attention is directed to the structure at the bottom of the door 2, which structure is shown in detail in Figures 2, 4, 5 and 6. It has been common practice heretofore to provide a 100

Z-bar at the bottom of a sliding door to protect same, one flange of said Z-bar being disposed on the outer surface of the door, and the other flange extending downwardly and forming a keeper means for the door. This prior construction has been open to the objection that water will find its way between the Z-bar referred to and the bottom of the door, resulting in the rapid deterioration of the door. According to the present invention, a construction is provided which avoids the forming of a pocket for the seepage and collection of water. Arranged at the bottom corners of the door are a pair of gussets 19, and arranged midway between said gussets 19 is the plate or plates 20, said gussets 19 and plate or plates 20 being bolted to said door and to the T-shaped member 15 by means of bolts 25-25. Each of said plates 20 is provided with a flange 21 at its bottom portion, which flange has an upturned tongue 22 fitting within a corresponding aperture 23 in the leg portion 15' of the T-shaped structure 15. By reason of this construction a sturdy structure is had which is not only very well adapted to withstand the shocks encountered in service, but which will minimize deterioration due to the water. The reason for the minimizing of the effects of weather above referred to will be obvious when it is considered that except for the relatively small region covered by the gussets 19-19 and the plate or plates 20, the outer surface of the door presents a clear shedding surface which will avoid the collection of water.

It will be clear that sliding movement of the door 2 may be accomplished with a minimum of friction, by reason of the rollers 4-4. The track member 5 may be readily secured to the structural steel member 7, which meets the standard of the American Railway Association. Said track member 5 not only provides a convenient bearing surface for the rollers 4-4, but also provides the downwardly extending flange 11 for cooperation with the flange 13 of the Z-bar 12 to limit outward movement of the door 2. Said flange 11 also performs valuable functions in stiffening said track member 5.

The present invention provides a structure which accords with preferred practice, which is simple to manufacture and assemble, and which is very little likely to jam in service.

Though a preferred embodiment of the present invention has been described in detail, it will be clear that many modifications will occur to those skilled in the art. It is intended to cover all such modifications that fall within the scope of the appended claims.

What is claimed is—

1. In combination, the frame of a railway car, a sliding door, guide means mounted upon said frame, a guide member mounted on the bottom of said door, said guide member comprising a T-shaped structure, the

bottom rear edge of said door being set into one of the angles of said T-shaped structure, a flange of said T-shaped structure being adapted to cooperate with the guide means on said frame, and a holding member mounted upon the outside of said door and having interfitting engagement with said T-shaped structure. 70

2. A railway car comprising a car frame and a sliding door, said car frame having attached thereto overhanging members for limiting the outward movement of said door, said door being provided with a pair of structural steel members adapted to cooperate with said overhanging members, one of said structural steel members having a re-entrant angle receiving the bottom rear edge of said door, the other of said structural steel members comprising a plate having interfitting engagement with said first mentioned structural steel member and bolted to said door. 80

3. In combination, the frame of a railway car, a sliding door, guide means mounted upon said frame, a guide member mounted on the bottom of said door, said guide member having a reentrant angle, the bottom rear edge of said door being set into said reentrant angle, and a holding member mounted on the outside of said door and having interfitting engagement with said guide member. 90

Signed at Chicago, Illinois, this 8th day of September 1926.

CARL E. EKLIND.

WILLIAM W. DARROW.
